UNITED STATES PATENT OFFICE

ARTHUR J. SCHMITT, OF CHICAGO, ILLINOIS

DESIGN FOR A COMBINED CONNECTED LAMP SOCKET AND HEATER ELEMENT

Application filed July 29, 1929. Serial No. 32,231. Term of patent 14 years.

To all whom it may concern:

Be it known that I, ARTHUR J. SCHMITT, a citizen of the United States, residing at Chicago, Illinois, have invented a new, original, and ornamental Design for a Combined Connected Lamp Socket and Heater Element, shown in elevation in the accompanying drawing.

The figure of the drawing illustrates the design in side elevation.

I claim:—

The ornamental design for a combined connected lamp socket and heater element as shown.

ARTHUR J. SCHMITT.
